US0D1066125S

(12) **United States Design Patent** (10) Patent No.: **US D1,066,125 S**
(45) Date of Patent: ** Mar. 11, 2025

(54) **CAR**

(71) Applicant: **BYD Company Limited**, Guangdong (CN)

(72) Inventors: **Yubo Lian**, Shenzhen (CN); **Wolfgang Josef Egger**, Shenzhen (CN); **Jihan Fan**, Shenzhen (CN); **Yaoping Wen**, Shenzhen (CN); **Peng Hu**, Shenzhen (CN)

(73) Assignee: **BYD COMPANY LIMITED**, Shenzhen (CN)

(**) Term: **15 Years**

(21) Appl. No.: **29/844,635**

(22) Filed: **Jun. 30, 2022**

(30) **Foreign Application Priority Data**

Dec. 30, 2021 (CN) 202130872300.X

(51) LOC (15) Cl. **12-08**

(52) U.S. Cl. ..... **USPC D12/92**
